E. WILLETT.

HAND GRASP.

APPLICATION FILED JULY 26, 1920.

1,376,126.

Patented Apr. 26, 1921.

UNITED STATES PATENT OFFICE.

ELSIE WILLETT, OF ALBERTON, MONTANA.

HAND-GRASP.

1,376,126.

Specification of Letters Patent. Patented Apr. 26, 1921.

Application filed July 26, 1920. Serial No. 398,940.

To all whom it may concern:

Be it known that I, ELSIE WILLETT, a citizen of the United States, residing at Alber-ton, in the county of Mineral and State of 5 Montana, have invented certain new and useful Improvements in Hand-Grasps, of which the following is a specification, reference being had to the accompanying drawings.

10 This invention relates to certain improvements in hand grasps and has relation more particularly to a device of this general character especially designed and adapted for use in connection with bails such as are em-15 ployed in conjunction with preserving ket-tles, pails, water buckets, and kindred uten-sils, and it is an object of the invention to provide a novel and improved device of this 20 general character which can be applied to a bail without the necessity of removing the bail from the vessel or other article to which it may be applied.

Another object of the invention is to pro-25 vide a novel and improved device of this general character embodying an elongated member having a bore therethrough with an entrance slot in communication with said bore, together with a plug adapted to close said slot after the hand grasp has been ap-30 plied to a bail and wherein means are pro-vided for holding said applied plug against displacement.

The invention consists in the details of 35 construction and in the combination and ar-rangement of the several parts of my im-40 proved hand grasp whereby certain impor-tant advantages are attained and the device rendered simpler, less expensive and other-wise more convenient and advantageous for use, as will be hereinafter more fully set forth.

The novel features of my invention will hereinafter be definitely claimed.

In order that my invention may be the 45 better understood, I will now proceed to de-scribe the same with reference to the accom-panying drawings, wherein:

Figure 1 is a longitudinal sectional view 50 taken through a hand grasp constructed in accordance with an embodiment of my in-55 vention and in applied position, the coact-ing bail or kindred member being shown in fragment and in elevation.

Fig. 2 is a view in top plan of my im-

proved hand grasp unapplied, with the plug 55 removed.

Fig. 3 is a view in end elevation of the structure as shown in Fig. 1 with the bail or kindred member in section.

Fig. 4 is a sectional view taken substan-tially on the line 4—4 of Fig. 2.

Fig. 5 is a view in elevation of the inner face of an end cap embodied in my pres-ent invention removed, and

Fig. 6 is a transverse sectional view taken 65 through a hand grasp constructed in ac-cordance with another embodiment of my in-vention.

As disclosed in Figs. 1 to 5 of the accom-panying drawings, my improved hand grasp 70 comprises an elongated body B of desired configuration and which has extending lon-gitudinally therethrough at substantially 75 its axial center a bore 1 with which com-municates a slot 2 extending the entire length of the body B and open at its opposite end with the side walls of said slot converging toward the center of the body B, with the space between the inner longitudinal mar-gins of the slot 2 of a width sufficient to 80 readily permit the passage through the slot 2 into the bore 1 of a bail 3 or kindred member.

After the body B has been applied to the bail 3 or the like, a plug 4 is snugly fitted 85 within the slot 2, said plug being of a length co-extensive with the length of the body B with the outer face of the plug sub-stantially in continuity with the peripheral 90 face of the body B.

The body B and the applied plug 4 are provided adjacent their opposite ends with the circumferentially disposed grooves or channels 5 in each of which snugly engages an inwardly disposed bead or corrugation 6 95 extending around the free marginal portion of the flange 7 of a cap C. A cap C snugly engages an end portion of the body B and is adapted to have rotary movement there-around and each of said caps C is provided 100 with a cut-away portion 8 adapted to regis-ter and substantially coincide with an end of the slot 2, and the inner part of the cut-away portion 8 terminates in a parti-circular opening 9 in which the bail 3 or the like 105 is adapted to seat when the hand grasp is applied thereto. In the present embodiment of my invention and particularly as illus-

trated in Fig. 5, the opening 9 is in the form of a semi-circle and said opening 9 is defined by an inwardly disposed flange 10 adapted to extend within the adjacent end 5 portion of the bore 1 of the body B.

Before the body B is applied to the bail 3 or the like, the plug 4 is separated and the caps C are adjusted to have the cut-away portions 8 thereof in register with the 10 ends of the slot 2 in said body B. After the body B has been applied to the bail 3 or the like, the plug 4 is applied and the caps C then rotated, so that the flanges 7 thereof will overlie the end portions of the 15 plug 4 and thereby hold the same against displacement.

In practice, it is preferred that each of the caps C be given substantially a one-half turn so that the plate P may be seated 20 within the cut-away portions 8 to hold or lock the caps C against rotation. Each of the plates P is secured to an end of the body B at a point substantially diametrically opposed to the slot 2 and the outer end of 25 said plate is provided with an angular extension 11 which overlies the periphery of the body B and is suitably secured thereto. The inner end portion of the plate P is provided with the inwardly disposed extension 12 which snugly engages within the 30 adjacent end portion of the bore 1 of the body B and which extension is continued to provide an elongated spring member 14 which has contact with the portion of the 35 bail 3 or the like within the bore 1 of the applied hand grasp.

The springs 14 serve as anti-rattlers and also provide means to facilitate the removal 40 of the hand grasp when desired as upon returning the cap C to bring the portions 8 thereof into register with the ends of the slot 2, the springs 14 will cause a relative movement of the body B and bail 3, whereby the plate P will be partially extended out 45 of the slot 2.

It is to be understood, however, that it is primarily intended that when my improved 50 hand grasp is applied to a bail, such mounting is to be considered substantially permanent.

In the form of my invention particularly illustrated in Fig. 6, the slot 2' of the body B' is dovetailed with the plug 4' of a corresponding configuration in cross section, 55 and the plug 4' is applied by endwise movement through an end of the slot 2'.

From the foregoing description it is thought to be obvious that a hand grasp constructed in accordance with my invention 60 is particularly well adapted for use by reason of the convenience and facility with

which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. As a new article of manufacture, a hand grasp comprising an elongated tubular body having a longitudinally disposed slot in communication with the bore thereof, a plug snugly fitting within the slot, caps rotatably supported by the end portions of the body, each of said caps being provided with a cut-away portion adapted to register 80 and substantially coincide with adjacent ends of the bore and slot of the body when the cap is in one position, and a plate carried by each end portion of the body and snugly fitting within the cut-away portions 85 of the caps when said caps are in a second position to hold the caps against rotation.

2. As a new article of manufacture, a hand grasp comprising an elongated tubular body having a longitudinally disposed slot 90 in communication with the bore thereof, a plug snugly fitting within the bore, caps rotatably supported by the end portions of the body, each of said caps being provided with a cut-away portion adapted to register 95 and substantially coincide with adjacent ends of the bore and slot of the body when the cap is in one position, and a plate carried by each end portion of the body and snugly fitting within the cut-away portions 100 of the caps when said caps are in a second position to hold the caps against rotation, each of said caps being provided with a resilient member extending within the bore of the body.

3. As a new article of manufacture, a hand grasp adapted for use in connection with a bail or kindred element, said hand grasp comprising an elongated tubular body provided with a longitudinally disposed slot in communication with the bore thereof, said bail being insertible within the bore of the body through the slot thereof, a plug for closing said slot, and caps engaged with the opposite end portions of the tubular body for holding the plug in applied position, each of said caps being provided with a resilient arm extending within the bore of the body for contact with the bail.

In testimony whereof I hereunto affix my 120 signature.

ELsie WILLETT.
